DISPLAY ACTUATING MECHANISM

Arthur J. Evers, Chicago, Ill., assignor to Arvey Corporation, Chicago, Ill., a corporation of Illinois

Application June 11, 1934, Serial No. 729,998

4 Claims. (Cl. 40—33)

This invention relates to improvements in display actuating mechanisms and refers specifically to a mechanism for simultaneously actuating or animating an advertising display by imparting thereto a plurality of motions of different characters.

The utility, objects and advantages of my invention will be apparent from the accompanying drawings and following detail description.

10 In the drawings, Fig. 1 is a side elevational view, illustrating the actuating mechanism comprising my invention, driving a display shown diagrammatically.

15 Fig. 2 is a top plan view of the actuating mechanism.

Fig. 3 is a top plan sectional view showing the gear trains associated with the mechanism.

Fig. 4 is a sectional view taken on line 4—4 of Fig. 3.

20 Referring in detail to the drawings, 1 indicates a casing which may comprise two substantially symmetrical metal shells 2 and 3. Each shell may be provided with an outwardly extending peripheral flange 4, said flanges being provided 25 with a plurality of registering apertures 5 through which bolts 6 may pass serving to secure the shells 2 and 3 together. The casing 1 may be supported upon legs or standards 7, which may comprise metal bands bent in rectangular 30 fashion in order to form three supporting sides, the ends of the bands being secured to the lower shell 3 by means of bolts 8. Each of the sides of the bands 7 may be provided with apertures 9 whereby said bands may be bolted or otherwise 35 fastened to a suitable support. The legs 7 being rectangular in shape provide means whereby the casing 1 may be positioned horizontally as shown in Fig. 4, or said casing may be disposed upon either of its longitudinal edges.

40 An electric motor 10 may be positioned beneath the casing 1 and between the supports 7. A pair of rods (not shown) may be secured in spaced relationship to the lower shell 3, said rods being threaded at their upper ends and engaged 45 with nuts 11 within casing 1. The rods may depend from shell 3 upon each side of motor 10 and may pass through the field pieces 12 of said motor. Nuts 13 may be positioned upon said rods immediately beneath shell 3 and may serve to hold said rods in rigid position with respect to said shell. Sleeves 14 and 15 may circumscribe said rods and may serve to properly space the field pieces 12 from the lower face of the shell 3.

Cross members 16 and 17 may be secured to 55 said rods at the lower and upper ends thereof,

said cross members intermediate their length, carrying bearings (not shown) which serve as journals for the armature shaft 19 of motor 10. An arm 20 may be positioned upon each of said rods and may be confined upon said rods between 5 the lower spacer 15 and cross member 16. Each of the arms 20 at their opposite ends may support brush holders 21, brushes 22 for the motor being positioned within said holders and being adapted to make contact with commutator 23. A 10 fan 24 may be disposed at the lowermost end of shaft 19 and may serve to provide an air circulation for the cooling of said motor.

Shaft 19 at its upper extremity may project through the wall of shell 3 and may carry at its 15 upper end pinion 25. Pinion 25 meshes with gear 26 carried upon shaft 27, the ends of which latter may be journaled in bearings 28 and 29 at its lower and upper end respectively, said bearings being secured by pressing in the walls of shells 20 3 and 2. A pinion 30 may also be positioned upon shaft 27 and is adapted to mesh with gear 31 mounted upon shaft 32, the upper and lower ends of which are respectively journaled in bearings 33 and 34, which, similar to bearings 28 and 29, are positioned in the walls of shells 2 and 3. A pinion 35 is also carried by shaft 32 and is adapted to mesh with gear 36 mounted upon shaft 37 which may be journaled in the upper 25 and lower shells 2 and 3. Shaft 37 upon which gear 36 is mounted, projects above the surface of shell 3, and, as will be hereinafter more fully described, may be utilized to drive in a continuous manner a desired display.

30 A segmental plate 38 may be rigidly mounted upon shaft 37 and an arm 39 may be formed integral with said plate, said arm being offset below the plane of the segmental portion 40 of the plate. A rotatable pin 41 may be disposed at the 35 end of arm 39 and upon rotation of shaft 37 said pin is adapted to engage in slots provided in the periphery of Geneva gear 43. Gear 43 may be mounted upon shaft 44 which may be journaled in bearings 45 and 46 respectively mounted in 40 the shells 3 and 2.

45 A sleeve 47 may be positioned upon shaft 44 and may be adapted to hold gear 43 in desired position within the casing 1, that is, in the plane of the segmental portion 40 of plate 38. Slots 50 50 42 may extend radially in gear 43 and may be circumferentially spaced from each other. The periphery of gear 43 intermediate each pair of slots is cut away in an arc-shaped manner as indicated at 48 in Fig. 3, the radius of curvature 55

of the arc being similar to the radius of curvature of the segmental portion 40 of plate 38.

Motor 10 may be energized by connecting plug 49 to a suitable source of electric current and upon rotation of said motor, shaft 37 is rotated. By means of the gear train comprising pinions 26, 30, and 35, and gears 26, 31, and 36, shaft 37 will be rotated at a very low speed. However, the rotation of shaft 37 is continuous during the period in which motor 10 is energized. When shaft 37 rotates arm 39 is revolved and the radius of said arm, that is, the distance between the center-line of shaft 37 and the center-line of pin 41, is such with respect to the radius of the Geneva gear 43 and the circumferential spacing of slots 42 from each other, that upon one complete rotation of shaft 37 taking place, gear 43 will be moved a circumferential distance equal to the distance between adjacent slots 42. During the remaining cycle of rotation of shaft 37, the segmental portion 40 of plate 38 engages the cut away portions 48 of gear 43, but no motion is imparted to said latter gear. It can readily be seen that while shaft 37 rotates continuously, shaft 44 will move intermittently, the number of individual movements necessary to complete one revolution of shaft 44 depending upon the number of slots 42 provided in the periphery of gear 43.

A plate 50 may be removably mounted upon the upper end of shaft 44 and may be secured to said shaft by means of set-screw 51. It is to be understood, however, that plate 50 may be dispensed with and a gear, pulley or crank arm (not shown) may be mounted upon shaft 44.

In the intended use of my invention, two associated movable advertising display elements may be actuated simultaneously. For example, a hexagonal prismatic display device 52 having six display faces 53, may be mounted upon plate 50 and secured thereon by means of screws 54 or the like. A sheave wheel 55 may be mounted upon the projecting end of shaft 37 and a belt or cord 56 may connect sheave wheel 55 to sheave wheel 57 which, in turn, may be mounted upon the connecting shaft 58, the opposite end of said shaft carrying a sheave wheel 59. Wheel 59 may be operatively connected to sheave wheel 60 by means of belt or cord 61. Wheel 60 may be mounted upon shaft 62 which, in turn, may carry one or more cylinders 63 whose lateral sides may be utilized as display surfaces.

It can readily be seen that by this arrangement prism 52 will be rotated intermittently whereby faces 53 will be sequentially presented as viewed from one side of the display. Simultaneously cylinders 63 will be continuously rotated and may also be viewed from the same point of view. This arrangement of an animated or mechanical display has been found to be very flexible and susceptible to being used in many attractive combinations. For instance, cylinder 63 may present or display a message which may be explanatory of a sequence of events which

may be illustrated upon adjoining faces 53 of the prism.

It is to be understood, of course, that I do not wish to be limited to the particular structural features illustrated in Fig. 1, since many combinations of movable displays wherein various elements of the display move continuously or intermittently may be used. Furthermore, the manner of driving the display from the actuating mechanism is shown diagrammatically in Fig. 1 and is presented merely for purposes of illustration.

I claim as my invention:

1. A display actuating mechanism casing, comprising in combination a pair of oppositely disposed symmetrical shells adapted to be secured together in fixed relation and within which an actuating mechanism is disposed, depending legs associated with one of said shells and extending perpendicularly therefrom and adapted to house a mover for said actuating mechanism between them, said depending legs being formed to present a plurality of alternating supporting base surfaces for the entire casing. 15

2. A display actuating mechanism casing, comprising in combination a pair of oppositely disposed symmetrical shells adapted to be secured together in fixed relation and within which an actuating mechanism is disposed, rectangular shaped depending legs associated with one of said shells and extending perpendicularly therefrom and adapted to house a mover for said actuating mechanism between them and an animatable display extending over the face of the other shell, said depending legs being formed to present a 35 plurality of alternating supporting base surfaces for the entire casing. 25

3. A display actuating mechanism casing, comprising in combination a pair of oppositely disposed symmetrical shells adapted to be secured together in fixed relation and within which an actuating mechanism is disposed, a three sided base support associated with one of said shells extending perpendicularly therefrom and adapted to house a mover for said actuating mechanism and an animatable display extending from the face of the opposed shell, said support being formed to present a plurality of alternating base surfaces for the entire casing. 40

4. A display actuating mechanism, comprising in combination a pair of oppositely disposed symmetrical shells adapted to be secured in fixed relation, an actuating mechanism within said casing comprising a plurality of shafts, symmetrically positioned bearings carried by each shell, 55 depending legs associated with one of said shells and extending perpendicularly therefrom adapted to house a mover for said actuating mechanism and an animatable display extending from and over the face of the other shell, said depending legs being formed to present a plurality of alternating base surfaces for the entire casing. 60

ARTHUR J. EVERE
